CLAIM

The ornamental design for a cervical brace, as shown and described.

DESCRIPTION

FIG. 1 is a rear right perspective view of a cervical brace of the present invention with the chin bridge in a closed condition;
FIG. 2 is a front left perspective view thereof;
FIG. 3 is a bottom view thereof;
FIG. 4 is a top view thereof;
FIG. 5 is a rear elevation view thereof;
FIG. 6 is a front elevation view thereof;
FIG. 7 is a left elevation view thereof;
FIG. 8 is a rear right perspective view of the cervical brace of the present invention with the chin bridge in an open condition;
FIG. 9 is a front left perspective view thereof;
FIG. 10 is a front elevation view thereof;
FIG. 11 is a rear elevation view thereof;
FIG. 12 is a right elevation view thereof;
FIG. 13 is a left elevation view thereof;
FIG. 14 is a bottom view thereof;
FIG. 15 is a top view thereof; and,
FIG. 16 is an exploded perspective view thereof.
The broken lines illustrate portions of the cervical brace that form no part of the claimed design.

1 Claim, 16 Drawing Sheets
